ATTORNEY

UNITED STATES PATENT OFFICE

JOHN W. FITZ GERALD, OF MILWAUKEE, WISCONSIN, ASSIGNOR TO BRIGGS & STRATTON CORPORATION, OF MILWAUKEE, WISCONSIN, A CORPORATION OF DELAWARE

LOCK

Application filed October 5, 1931. Serial No. 566,977.

This invention relates to certain new and useful improvements in locks and refers more particularly to key controlled tumbler locks.

It is an object of this invention to provide means for positively securing the lock cylinder against unlocking movement in the event of forced or unauthorized actuation of the lock cylinder.

Another object of this invention resides in the provision of a normally dormant locking element which is shiftable to a position positively restraining unlocking movement of the lock cylinder upon any movement of the lock cylinder not produced with the proper key.

With the above and other objects in view which will appear as the description proceeds, this invention resides in the novel construction, combination and arrangement of parts substantially as hereinafter described and more particularly defined by the appended claims, it being understood that such changes in the precise embodiment of the hereindisclosed invention may be made as come within the scope of the claims.

In the accompanying drawings one complete example of the physical embodiment of this invention is illustrated constructed according to the best mode so far devised for the practical application of the principles thereof, and in which:

Figure 1 is a side elevation of a lock structure embodying this invention with parts broken away and in section;

Figure 2 is a cross section view taken through Figure 1 on the plane of the line 2—2;

Figure 3 is a view similar to Figure 1 and illustrating the locking element in operative position;

Figure 4 is a perspective view of the locking element; and

Figure 5 is a transverse section through the lock structure mounting member.

Referring now more particularly to the accompanying drawings, the numeral 5 represents a mounting member of suitable design having a bore 6 to receive a lock cylinder 7. The outer end of the bore 6 is counterbored as at 8 and the outer end of the lock cylinder

has an enlarged head 9 which is received in the counterbore.

Formed in the mounting member in communication with the bore 6 is a longitudinal groove 10 into which a plurality of tumblers 11 carried by the lock cylinder are yieldably urged by springs 12 to secure the lock cylinder against rotation in the bore. The tumblers 11 are retractable out of the longitudinal groove 10 to free the lock cylinder for rotation upon the insertion of a proper key, not shown, into a key opening 13 in the lock cylinder.

The rotation of the lock cylinder may be transmitted through a cam or driving member 14 eccentrically extended from the inner end of the cylinder to any desired locking mechanism, not shown.

Directly alongside the tumbler receiving groove 10 and forming a sidewise extension thereof, is another longitudinal groove 15. This groove, as best illustrated in Figures 2 and 5, has its bottom stepped to form a deep channel 16 and a shallow portion 17 with the shallow portion 17 juxtapose the groove 10. The shallow portion 17 is of less depth than the tumbler receiving groove 10 and thus forms a longitudinal ledge 18 between the two grooves.

This ledge 18 is of sufficient depth for the locking tumblers to engage when in their projected positions to prevent accidental rotation of the lock cylinder, but is low enough so that even a slight rotational force applied to the lock cylinder as by a screw driver or other implement inserted in the key way during an attempt to force the lock, permits the projecting ends of the tumblers to move into the groove 15.

This movement of the tumblers into the groove 15 moves a locking bar 19, slidably mounted in the groove, to an operative position positively locking the lock cylinder against further rotation toward unlocking position, as will be later described. The locking bar 19 is in the form of a comb and comprises a solid back 20 and teeth 21.

As best illustrated in Figure 2, the cross-sectional shape of the locking bar is such as to completely fill the groove 15 with one side

of the back and teeth forming a curved surface tangential to the wall of the bore 6. The opposite side of the locking bar which engages the bottom of the groove 15 is stepped 5 to correspond to the stepped shape of the groove bottom, with the teeth engaging the shallow portion 17 and the back received in the deeper channel 16. Inasmuch as the cross section of the locking bar completely 10 fills the groove 15, the lock cylinder and mounting member confine it in the groove and the engagement of its back in the deeper channel 16 guides the locking bar for longitudinal sliding movement in the groove and 15 holds the same against lateral movement out of its proper position into the groove 10 when the tumblers are retracted.

The outer end of the groove 15 like the groove 10 terminates with the bottom of the 20 counter-bore 8 with which a shoulder 22 formed at the juncture of the lock cylinder main portion with its outer enlarged head 9 engages, so that the outer end of both grooves 10 and 15 is closed by the shoulder 22. Consequently the shoulder 22 limits the outer 25 longitudinal movement of the locking bar.

Inward longitudinal movement of the locking bar is restricted by terminating the groove 15 as best illustrated in Figure 5. 30 The distance from the inner end 23 of the groove 15 to the shoulder 22 is slightly greater than the overall length of the locking bar so that a slight degree of play is afforded. But upon any rotation of the lock cylinder toward 35 unlocked position, which is in a counter-clockwise direction with respect to Figure 2, brought about without fully retracting all of the tumblers any one or more tumblers projecting beyond the lock cylinder, engage the 40 teeth of the locking bar and cause it to shift forwardly to engage its forward tooth 24, which is comparatively heavier than the remaining teeth, with a notch 25 formed in the shoulder 22. To effect this forward sliding 45 of the locking bar upon rotation of the lock cylinder and the engagement of the tumblers with the teeth, the back edges 26 of the teeth are inclined, and when the locking bar is in its normally inactive position, the plane of 50 the back edges of the teeth intersects and lies in the path of the transverse planes of the tumblers.

Hence as the cylinder is turned and the tumbler ends engage the inclined back edges 55 26 the cam action afforded thereby slides the locking bar forwardly to engage its forward end 24 in the notch 25.

The engagement of a locking bar end 24 with the notch 25 forms a rigid lock preventing 60 further rotation of the lock cylinder toward unlocking position, and as it is impossible to engage a tool inserted through the key way with the locking bar, the engagement of the bar with the notch 25 provides a 65 positive lock which cannot be defeated.

The only way in which the locking bar can be disengaged is by returning the lock cylinder to its fully locked position. During this movement the angle of the bottom 27 of the notch cams the locking bar rearwardly, the 70 forward end of the back 19 of the comb-like locking bar being inclined as at 28 to facilitate this action; and it is observed that when the lock cylinder is in its fully locked position the forward end 24 of the locking bar engages the flat shoulder 22 so that accidental shifting of the locking bar is impossible. 75

From the foregoing description taken in connection with the accompanying drawings, 80 it will be readily apparent to those skilled in the art to which an invention of the character described appertains that this invention affords a novel positive means for preventing "picking" of a tumbler lock or even forcing 85 the lock, for the locking bar may be of substantial proportions and as it is placed in direct compression between a mounting member carried abutment formed by one side of the groove 15 and a lock cylinder abutment provided by the notch 25, it is capable of 90 withstanding very great torsional force. It is also apparent that the incorporation of this locking bar to locks of the character described entails no radical changes in design and lends 95 itself readily to present manufacturing meth- 100 ods.

What I claim as my invention is:

1. A lock comprising a bored mounting member, a lock cylinder movable therein, tumblers adapted to normally secure the lock cylinder in a predetermined position in the mounting member bore, said tumblers being movable to free the lock cylinder for movement upon the insertion of a proper key into the lock cylinder, and means movable simultaneously upon movement of the lock cylinder while at least one of the tumblers is in any but fully inactive position, to a position interlocking the lock cylinder and mounting member to restrict such movement of the lock cylinder. 110

2. A lock comprising a bored mounting member, a lock cylinder movable therein, tumblers adapted to normally secure the lock cylinder in a predetermined position in the mounting member bore, said tumblers being movable to free the lock cylinder for movement upon the insertion of a proper key into the lock cylinder, and means movable to a position preventing movement of the lock cylinder beyond a predetermined degree in one direction by any one tumbler during movement of the lock cylinder in said direction while said tumbler is in any but fully inactive position. 115

3. A lock comprising a bored mounting member, a lock cylinder member movable in the mounting member bore, and a locking element at all times engaged with one of said members and movable into engagement with 120

the other member to interlock said members and prevent movement in one direction beyond a predetermined degree, by unauthorized movement of the lock cylinder in said direction.

4. A lock comprising a bored mounting member, a lock cylinder member movable in the mounting member bore, locking tumblers adapted to normally secure the lock cylinder

10 member against movement in the mounting member bore, a locking element at all times engaged with one of the members and movable into engagement with the other member to interlock said members and prevent move-

15 ment of the lock cylinder beyond a predetermined degree in one direction, and means carried by the locking element and engageable by any locking tumbler in any but fully inactive position upon movement of the lock cylinder 20 in said direction while said tumbler is in said position for moving the locking element to interlock the members.

5. A lock comprising a mounting member, a lock cylinder movable therein, locking tumblers adapted to normally secure the lock cylinder in locked position said locking tumblers being retractable to free the lock cylinder for movement from locked position upon the insertion of a proper key, and a locking element movable to a position securing the lock cylinder against movement beyond a predetermined degree in one direction by any locking tumbler in any but fully retracted position during movement of the lock cylinder 35 in said direction.

6. A lock comprising a bored mounting member, a lock cylinder rotatable in the mounting member bore, locking tumblers for securing the lock cylinder in a locked position and retractable to free the lock cylinder for movement from locked position upon the insertion of a proper key, and a locking element for securing the lock cylinder against movement in one direction independently of the tumblers, said locking element being movable to operative position upon movement of the lock cylinder from locked position effected while any locking tumbler is in any but fully retracted position.

50 7. A lock comprising a mounting member, a lock cylinder rotatable in the mounting member, locking tumblers for securing the lock cylinder against rotation in the mounting member and retractable to free the lock

55 cylinder for rotation upon the insertion of a proper key, a locking element engageable with the lock cylinder for securing the lock cylinder against rotation in one direction, and means whereby any locking tumbler in any but fully retracted position moves the locking element to said operative position upon rotation of the lock cylinder in said direction while said locking tumbler is in any but fully retracted position.

60 65 8. A lock comprising a mounting member,

a lock cylinder rotatable in the mounting member, locking tumblers for securing the lock cylinder against rotation in the mounting member and retractable to free the lock cylinder for rotation upon the insertion of a proper key, a locking element movable to a position securing the lock cylinder against rotation in one direction, and means on said locking element and engageable by any locking tumbler in any position other than fully retracted position for moving the locking element into operative position upon rotation of the lock cylinder while said locking tumbler is in said position.

9. A lock, comprising a bored mounting member, having a tumbler receiving groove communicating with its bore, a lock cylinder rotatable in the mounting member bore, locking tumblers carried by the lock cylinder and engageable in said groove to secure the lock cylinder against rotation, said tumblers being retractable by the insertion of a proper key into the lock cylinder to free the lock cylinder for rotation, and the tumbler receiving groove being of greater width than the tumblers whereby a limited rotation of the lock cylinder is possible while the tumblers are projected to locking positions, a locking element movable to a position securing the lock cylinder against rotation in one direction, and means on the locking element and engageable by any tumbler to move the locking element to said position during the rotation of the lock cylinder through said limited degree with the locking tumblers projected.

10. A lock, comprising a bored mounting member, a lock cylinder rotatable therein, locking tumblers carried by the lock cylinder and adapted to secure the same against rotation, said tumblers being retractable to free the lock cylinder for rotation upon the insertion of a proper key into the lock cylinder, a locking element longitudinally shiftable to a position securing the lock cylinder against rotation in one direction beyond a predetermined degree, and means carried by the locking element engageable by any one locking tumbler during rotation of the lock cylinder in said degree effected while said locking tumbler is in any but fully retracted position for shifting the locking element to operative position.

11. A lock comprising a mounting member, a lock cylinder in the mounting member and movable therein by a key inserted into the lock cylinder, a locking element movable to a position securing the lock cylinder against movement in one direction beyond a predetermined degree, and cooperating means carried by the locking element and the lock cylinder for moving the locking element to said position upon movement of the lock cylinder effected in any other manner except by the proper key.

12. A lock comprising a bored mounting

member, a lock cylinder in the mounting member bore, locking tumblers for holding the lock cylinder against rotation and retractable to free the lock cylinder for rotation upon the insertion of a proper key into the lock cylinder, a locking element longitudinally movable in the mounting member and having a surface forming substantially a continuation of the curved surface of the bore whereby the locking tumblers clear the same when in fully retracted position, and means on said locking element and engageable by any locking tumbler not fully retractable during rotation in one direction for moving the locking element to a position securing the lock cylinder against rotation in said direction beyond a predetermined degree.

13. A lock, comprising a bored mounting member, a lock cylinder in the mounting member bore and movable to and from a locked position, locking tumblers for securing the lock cylinder in said locked position, said locking tumblers being retractable to free the lock cylinder for movement from said locked position upon the insertion of a proper key, a locking element movable to a position securing the lock cylinder against movement from locked position, and means for moving the locking element to said position during movement imparted to the lock cylinder by any means other than the proper key.

14. A lock, comprising a bored mounting member, a lock cylinder in the mounting member bore and movable to and from a locked position, locking tumblers for securing the lock cylinder in said locked position, said locking tumblers being retractable to free the lock cylinder for movement from said locked position upon the insertion of a proper key, a locking element movable to a position securing the lock cylinder against movement from locked position, and means carried by the locking element and engageable by any locking tumbler during movement of the lock cylinder effected by any means other than the proper key for moving the locking element to said position.

15. A lock comprising a bored mounting member, a lock cylinder in the mounting member bore and movable to and from a locked position, locking tumblers for securing the lock cylinder in locked position and movable to inactive positions to free the lock cylinder for movement from locked position upon the insertion of a proper key into the lock cylinder, a locking element movable to a position securing the lock cylinder against movement from locked position, and an abutment carried by the locking element and having an inclined surface engageable by a locking tumbler during movement of the lock cylinder while said locking tumbler is in any but fully inactive

position, for moving the locking element to its operative position.

16. A lock cylinder comprising a bored mounting member, an abutment on the mounting member, a lock cylinder rotatable in the mounting member bore, an abutment carried by the lock cylinder, locking tumblers for securing the lock cylinder in locked position and retractable upon the insertion of a proper key to free the lock cylinder for rotation from locked position, a locking element at all times engaged with one of the abutments and movable into engagement with the other abutment to secure the lock cylinder against movement from locked position, and means for moving the locking element upon rotation of the lock cylinder effected while any locking tumbler is in any but fully retracted position.

17. A lock comprising a mounting member, a lock cylinder movable in the mounting member, locking tumblers for securing the lock cylinder in locked position at which the lock cylinder has a limited degree of movement with respect to the mounting member, said locking tumblers being movable to inactive positions to release the lock cylinder for movement from locked position upon the insertion of a proper key into the lock cylinder, a locking element movable to a position securing the lock cylinder against movement from locked position, and means for moving said locking element to its operative position during the limited movement in one direction of the lock cylinder effected in any manner other than by the use of the proper key.

18. In a lock including a mounting member, a lock cylinder member in the mounting member, locking tumblers for holding the lock cylinder member in a locked position and movable by a proper key to inactive positions freeing the lock cylinder member for movement from locked position, a locking element movable longitudinally with respect to the lock cylinder member to and from a position interlocking said members, and means for controlling the locking element from a locking tumbler so that movement of the lock cylinder member from its locked position with said tumbler in any but fully inactive position effects said interlocking.

19. In a lock including a mounting member, a lock cylinder member in the mounting member, locking tumblers for holding the lock cylinder member in a locked position and movable by a proper key to inactive position freeing the lock cylinder member for movement from locked position, a locking element interposed between said members and movable longitudinally with respect to the lock cylinder member to and from a position interlocking the said members, and means for controlling the locking element

- from a locking tumbler so that movement of the lock cylinder member from locked position with said tumbler in any but fully inactive position effects said interlocking.
- 5 20. In a lock including a mounting member, a lock cylinder member in the mounting member and movable from a locked position upon the insertion of a proper key therein, a locking element carried by one of 10 said members and movable longitudinally with respect to the lock cylinder member to and from a position interlocking said members, and means operable upon actuation of the lock cylinder member from locked position 15 by any means other than the proper key for effecting said interlocking.
21. In a lock including a mounting member, a lock cylinder member in the mounting member and movable from a locked position upon the insertion of a proper key therein, a locking element mounted in a groove in one of the members and extending longitudinally with respect to the lock cylinder member and juxtapose the other 25 member whereby said locking element is maintained in the groove by said other member, said locking element being longitudinally movable in the groove to a position interlocking said members, and means operable 30 upon actuation of the lock cylinder member from locked position by any means other than the proper key, for effecting said interlocking.
22. A lock comprising a bored mounting 35 member, a lock cylinder member movable in the mounting member bore to and from locked position upon the insertion of a proper key into the lock cylinder member, one of said members having a longitudinal 40 groove opening to the line of part between said members, a locking element longitudinally slidable in said groove to and from a position interlocking said members, and means operable upon actuation of the lock 45 cylinder member from locked position by any means other than the proper key for sliding the locking element to its position interlocking the members.
23. A lock comprising a bored mounting 50 member, a lock cylinder member movable in the mounting member bore to and from locked position, locking tumblers for holding the lock cylinder member in locked position, said tumblers being movable to inactive positions upon the insertion of a proper key 55 into the lock cylinder member to free the lock cylinder member for movement from locked position, one of said members having a longitudinal groove opening to the line of part 60 between said members, a locking element slidably mounted in said groove for movement to and from a position interlocking said members, and means for controlling the locking element from a locking tumbler 65 so that movement of the lock cylinder mem- ber from its locked position with said tumbler in any but fully inactive position longitudinally slides the locking element to interlocking position.
24. A lock comprising a bored mounting 70 member, a lock cylinder member in said mounting member bore and movable to and from a locked position, locking tumblers for holding the lock cylinder member in locked position and retractable upon the insertion of a proper key into the lock cylinder member to free the lock cylinder member for movement, said mounting member having a longitudinal groove opening to its bore and into which the locking tumblers are movable upon movement from locked position effected while the tumblers are in projected operative positions, and a locking element slideable in said groove to a position interlocking the members upon engagement therewith 75 of any tumbler moved into the groove.
25. A lock comprising a bored mounting 80 member, a lock cylinder member movable in the mounting member bore to and from a locked position, locking tumblers yieldably projected from the lock cylinder member for holding the lock cylinder member in locked position, said locking tumblers being retractable to free the lock cylinder member for movement upon the insertion of a proper 85 key into the lock cylinder member, said mounting member having a longitudinal groove opening to its bore and into which the tumblers are movable upon movement of the lock cylinder member from locked position while the tumblers are projected, a locking element in said groove and movable to a position interlocking said members, and means carried by said locking element and engageable by any projected locking tumbler 90 during movement of the lock cylinder member from its locked position while said tumbler remains projected for moving the locking element to operative position.
26. A lock comprising a bored mounting 95 member, a lock cylinder member movable in the mounting member bore to and from locked position, locking tumblers carried by the lock cylinder member for holding the lock cylinder member in its locked position, 100 said locking tumblers being retractable upon the insertion of a proper key into the lock cylinder member to free the same for movement, the mounting member having a longitudinal groove opening to its bore and closed 105 by the cylindrical surface of the lock cylinder member, a locking element in the groove of a cross section substantially filling the groove whereby the lock cylinder member maintains the locking element in the groove, 110 said locking element being movable longitudinally to a position interlocking the members, and inclined abutments on the locking element lying in the paths of the locking tumblers during movement of the lock cyl- 115
- 120
- 125
- 130

inder member from locked position effected while the tumblers are in any but retracted position, whereby the locking element is moved to its operative interlocking position 5 by any projected tumbler upon such movement of the lock cylinder member.

27. A lock comprising a bored mounting member having a longitudinal groove communicating with its bore, the bottom of the 10 groove being stepped and of less depth at its central portion than at its side edges to provide an abrupt ledge, a lock cylinder member rotatable in the mounting member bore, locking tumblers carried by the lock cylinder member and engageable in the 15 groove between one side thereof and said abrupt ledge, said locking tumblers being retractable within the lock cylinder member upon the insertion of the key to free the lock cylinder member for rotation, a locking element 20 slid able in the groove between said abrupt ledge and the other side of the groove, and maintained in the groove by the cylindrical surface of the lock cylinder member, and 25 means including any locking tumbler projecting beyond the lock cylinder member for sliding the locking member upon rotation of the lock cylinder member effected while said locking tumbler projects therebeyond.

30. 28. A lock comprising a bored mounting member, having a tumbler receiving groove communicating with its bore and a second groove juxtapose the tumbler receiving groove and forming a sidewise extension 35 thereof, said second groove being of less depth than the tumbler receiving groove at its juncture with the tumbler receiving groove to provide a longitudinal ledge, a lock cylinder member rotatable in the mounting member bore to and from a locked position, locking tumblers carried by the lock cylinder member and engageable in the tumbler receiving groove to hold the lock cylinder member 40 in locked position, said tumblers being movable into the second longitudinal groove upon disengagement from said ledge and being fully retractable within the lock cylinder member to free the lock cylinder member for rotation upon the insertion of a proper key 45 therein, a locking element slid able longitudinally in the second groove to and from a position interlocking the members, and means on said locking element and engageable by a tumbler projecting from the lock cylinder 50 member during movement of the lock cylinder member from locked position for moving the locking element to its position interlocking the members.

55. 29. A lock comprising a bored mounting member, a lock cylinder member rotatable in the mounting member bore, locking tumblers for holding the lock cylinder member in locked position and retractable within the lock cylinder member upon the insertion of a proper key therein to free the lock cylinder

member for rotation, a locking element longitudinally movable to and from a position interlocking said members, and teeth on said locking element having inclined portions lying in the path of the locking tumblers upon movement of the lock cylinder member from locked position while the tumblers are projected therefrom whereby engagement of any tumbler with said inclined portions during such movement of the lock cylinder member 70 moves the locking element to its operative position interlocking the members.

30. A lock comprising a bored mounting member, a lock cylinder member movable in the mounting member bore, locking tumblers for holding the lock cylinder member against movement, said locking tumblers being movable in planes transverse to the longitudinal axis of the lock cylinder member, a locking element movable longitudinally to a position 80 interlocking said members, and means for transmitting longitudinal movement to the locking element from the transverse movement of a locking tumbler.

31. A lock comprising a bored mounting member, a lock cylinder member rotatable in the mounting member bore, locking tumblers for holding the lock cylinder member in locked position, said tumblers being retractable to free the lock cylinder member for rotation upon the insertion of a proper key into the lock cylinder member and moving in planes transverse to the longitudinal axis of the lock cylinder member upon rotation of the lock cylinder member, a locking element 90 movable longitudinally with respect to the lock cylinder member axis to a position interlocking the members, and means for transmitting longitudinal movement to the locking element from said transverse movement 95 of any locking tumbler.

32. A lock comprising a bored mounting member, a lock cylinder in the mounting member bore, tumblers normally projected from the lock cylinder for holding the lock cylinder in locked position in the mounting member bore, a locking element carried by the mounting member, an abutment on a locking member, a second abutment on a lock cylinder, means carried by the locking element and engageable by the tumblers to slide the locking element to a position engaging its abutment with the lock cylinder carried abutment upon movement of the lock cylinder in one direction with the tumblers projected, and means operable to return the locking element to disengage its abutment from the lock cylinder abutment upon movement of the lock cylinder in an opposite direction.

33. A lock comprising a bored mounting member, a lock cylinder rotatable therein, locking tumblers carried by the lock cylinder to normally project therefrom and secure the lock cylinder against rotation, said locking tumblers being retractable to free the lock cyl-

- inder for rotation by the insertion of a proper key, a locking element carried by the mounting member, means carried by the locking element and engageable by any tumbler not in retracted position during rotation of the lock cylinder in one direction to move the locking element longitudinally, an abutment carried by the locking element, an abutment carried by the lock cylinder, said abutments being interlocked by such longitudinal movement by the locking element, and means operable upon rotation of the lock cylinder in the opposite direction for returning the locking element to its normal inactive position.
- 15 34. A lock comprising a bored mounting member, a lock cylinder mounted therein, transverse key operable tumblers carried by the lock cylinder to normally project therefrom and secure the lock cylinder against rotation, a locking member to secure the lock cylinder against rotation and adapted to be engaged by said tumblers and to be freed therefrom by the insertion of a proper key into the lock cylinder, and means including said tumblers for moving the locking member into a position securing the lock cylinder against rotation upon rotation of the lock cylinder toward unlocked position effected without the use of a proper key.
- 20 30. In testimony whereof I have hereunto affixed my signature.
